UNITED STATES PATENT OFFICE.

AUDUS N. SMITH, OF MORRISTOWN, TENNESSEE.

DESIGN FOR A COMBINATION WINDOW-SHADE FASTENER AND CURTAIN-POLE BRACKET.

46,297.

Specification for Design.

Patented Aug. 18, 1914.

Application filed May 28, 1914. Serial No. 841,663. Term of patent 7 years.

To all whom it may concern:

Be it known that I, AUDUS N. SMITH, a citizen of the United States, residing at Morristown, in the county of Hamblen and State of Tennessee, have invented a new, original, and ornamental Design for Combination Window-Shade Fasteners and Curtain-Pole Brackets, of which the following is a specification, reference being had to the accompanying drawing, forming part thereof.

The figure is a perspective view of a com-

bination window shade fastener and curtain pole bracket illustrating my new design.

I claim:

The ornamental design for a combination window shade fastener and curtain pole bracket, as shown.

AUDUS N. SMITH.
